Primary Examiner — Ryan Harvey(74) *Attorney, Agent, or Firm* — Husch Blackwell LLP(57) **CLAIM**

The ornamental design for a handle for a trampoline, as shown and described.

DESCRIPTION

FIG. 1 is a front perspective view of a handle for a trampoline showing the new design;

FIG. 2 is a top perspective view thereof;

FIG. 3 is a bottom plan view thereof;

FIG. 4 is a front perspective view thereof;

FIG. 5 is a rear perspective view thereof;

FIG. 6 is a right perspective view thereof; and,

FIG. 7 is a left perspective view thereof.

The broken lines in the drawings represent unclaimed environmental subject matter and form no part of the claim.

The circular ends of the two handles shown in FIGS. 6 and 7, are flat and unornamented.
